UNITED STATES PATENT OFFICE.

MILTON G. CLYMER AND ARTHUR E. RITCHIEY, OF ST. LOUIS, MISSOURI.

MACHINE FOR OPENING AND REFINISHING CANS.

1,317,001.

Specification of Letters Patent. Patented Sept. 23, 1919.

Application filed June 12, 1918. Serial No. 239,624.

To all whom it may concern:

Be it known that we, MILTON G. CLYMER and ARTHUR E. RITCHIEY, both citizens of the United States, and residing at St. Louis, 5 in the State of Missouri, have invented a certain new and useful Improvement in Machines for Opening and Refinishing Cans, of which the following is a specification.

This invention relates to a machine for 10 opening and refinishing cans.

Many commodities, such as canned fruits, are packed and shipped in cans, and in establishments manufacturing preserves, large 15 numbers of these cans must daily be opened to utilize the contents thereof. Now this not only requires considerable labor, but the open cans, when opened by the present methods and mechanisms employed are unfit for further use, and must, therefore, 20 be discarded and sold for junk, even though these cans may be in excellent condition and can readily be utilized. Furthermore, the cans, on account of being shipped, are often bent and dented considerably so as to not 25 only prevent their being effectively opened, but also used again.

One of the objects of this invention, therefore, is to provide a machine whereby the cans can be readily opened with a minimum 30 of labor and expense, and without damaging the contents thereof.

Another object is to provide a machine which will refinish and contour the opened edge of the can, so as to enable it to be subsequently used.

Further objects will appear from the detail description taken in connection with the accompanying drawings, in which,

Figure 1 is a side elevation of a machine 40 embodying this invention;

Fig. 2 is a plan of the support or table for the can;

Fig. 3 is an enlarged section on the line 3—3, Fig. 1, and showing the cutting and 45 refinishing head;

Fig. 4 is an enlarged section on the line 4—4, Fig. 1, showing the operating mechanism;

Fig. 5 is a detail of Fig. 3, showing the 50 operation of the mechanism in cutting a can head and refinishing its edge;

Fig. 6 is a view of a can head;

Fig. 7 is a similar view, but showing the head partially severed;

Fig. 8 is a section on the line 8—8, Fig. 6; 55
Fig. 9 is a section on the line 9—9, Fig. 7;

Fig. 10 is a view similar to Fig. 9, but showing the head completely severed, and the edge completely refinished, with the rim positioned thereover; and, 60

Fig. 11 is a view similar to Fig. 10, but showing the rim in final attached position, and the cover in place.

Referring to Figs. 1 to 5 inclusive, 1 designates a machine frame or column, which 65 has a bracket 2 adapted to support a table 3, which is mounted on a shank 4, sliding vertically in a bearing 5 on the bracket 2. The shank 4 is connected to one end of a lever 6, pivoted intermediate its ends at 70 7 on the frame 1, and connected at its other end by a link 8 with a lever 9, pivoted on a bracket 10 on the base 11 of the machine frame. The arm 9 is provided with a slot or guideway 12, engaged by a pin 13 on 75 the disk 14, loosely mounted on a shaft 15, which in turn is mounted for rotation in a bearing 16 on the base 11. The shaft 15 is provided with a pulley 17, which is fixed to and drives the shaft, and this shaft is 80 further provided with a clutch 18, controlled by the usual wedge 19, which is connected by a bell-crank lever 20 and a link 21, with the treadle 22 on the base. Upon depression of the treadle the clutch is shifted 85 to connect the disk 14 with the shaft, and cause a vertical reciprocation with the table 3, as hereinafter described.

Mounted on the frame 1 is an overhanging bracket 23, which has a bearing 24 90 adapted to receive a shank 25 of a head 26, positioned directly over the table, the head being adapted for adjustment vertically by the sliding engagement of the shank 25 with the bearing 24, this head being locked in 95 adjusted position by a set screw 27.

The head comprises an annular guide 28 which flares at its lower end as shown at 29, to take over the can. Arranged inside of this head is a cutter 30, which has a 100 serrated cutting edge 31, adapted to cut the head of the can. It will be noted that the cutter is spaced from the guide, and that the annular recess between the cutter and the guide extends beyond and past the 105 termination of the cutting edge of the cutter, as shown at 32, for a purpose herein-after to be described. The table 3 is pro-

vided with positioning guides 33, which is adapted to position a can underneath and in correct coöperative relation with respect to the head 26. When, therefore, this can 5 C is in position on the table, and the treadle 22 is depressed, the table will rise and force the can into coöperative relation with the head. This will cause the can to enter the flaring guide 28—29, and rise therein until 10 the head of the can is engaged by the serrated edge 31 of the cutter 30, which will cause the cutter to cut the can head along and at a definite and predetermined distance from the outer edge of the can. During 15 the first part of the movement, the cutter will puncture the can head at numerous points, and cut along the edge until the head is completely severed. Thereafter, further movement will cause the cut can 20 edge and the rim to enter the space 32, between the cutter and the guide, so as to force the rim therein, and press and wipe the cut edge against the inside face of the can body, as shown in Fig. 5. This action 25 will concurrently straighten out the bent edge of a can, and contour the rim so as to make the finished edge a perfect circle, with both the outside and the inside edges of the rim refinished. When the table again 30 drops, the can will drop with it partly by its weight and partly due to the wedge connection with the guides 33, and can then be removed from the table, the head which is now loose in the can taken out, and the 35 contents discharged.

Figs. 6 to 11 inclusive illustrate more fully the method employed, of cutting and refinishing the can. In Fig. 7 the head H of the can has been partially cut by the serrated 40 cutting edge 31, as shown at A, and the cut edge has been partially bent against the inside face of the can body. Fig. 10 shows the cut edge B completely pressed against the inside face of the can body, and it will be 45 noted that in view of the fact that this action takes place while the can is engaged on the outside by the guide, and while the can is thus supported, the edge B is pressed uniformly around and against the face of 50 the can body, so as to form a completely refinished inside edge. Concurrently, the outer edge of the can, that is, the folded over part D of the head rim, has been refinished and contoured and made perfectly circular 55 by the engagement of the inside face of the guide therewith. Accordingly, both the inside and outside faces of the rim have been refinished, and this finish is smooth, on account of the wiping action of the cutter and 60 of the guide. There is thus provided a smooth circular rim which is refinished on both its outside and its inside faces.

During the first or cutting operation, the points will first penetrate the can head, each 65 point cutting from its center outwardly with

a draw cut and causing the metal of the head or center part to curl, as shown in Figs. 7 and 9; and the last part of the cutting operation is a tearing operation at the points of connection between the center part and the 70 rim. The center part does not, therefore, enter that part of the cutter above the bases of the U recesses formed by the teeth of the serrated edge 31, but these bases tear the points of connection loose, thereby permitting the cut center part to drop down into the can, where it can readily be picked out, especially since the wiping action, heretofore described, has pressed the inside cut portion against the can body, and has therefore, 80 widened the mouth of the open can. By adjusting the head 26 vertically on the bracket 23, the extent of movement of the can body into the head can be adjusted to correspond with the height of a can to be opened. This 85 adjustment also governs the extent of the wiping action. It will be understood that since the metal of which cans are generally made, is comparatively ductile and not 90 springy, the bending and shaping of the can edge, will cause these parts to remain in shaped position; so that upon retracting movement of the table, the can will readily drop with it out of engagement with the head 26 and the cutter therein. 95

In order to provide a rim which can be readily closed by a cover, a formed rim E, having a finished inside face F, is placed over the refinished rim of the can, and the outer flange G is folded over the can, or in 100 any suitable manner, so as to make a firm attachment thereto. This can be done in any suitable manner. The can is thus provided with a finished rim which can receive a suitable cover 1. 105

It will thus be seen that the invention accomplishes its objects. The machine is simple in construction and operation, and not only will it rapidly cut the head out of a can without disturbing its contents, but the cut edge is so refinished and the rim is so contoured as to provide a container which can be used again, and which is in fact just as good as new. 110

It is obvious that various changes may be 115 made in the details of construction without departing from the spirit of this invention. It is, therefore, to be understood that this invention is not to be limited to the specific details described and shown. 120

Having thus described the invention, what is claimed is:

1. In a machine of the class described, the combination with an annular guide adapted to engage and encircle the outside of a can 125 so as to sustain the same along its edge, of an annular cutter positioned inside of said guide and adapted to cut the can along but inside of its sustained edge.
2. In a machine of the class described, the 130

combination with an annular guide adapted to take over the head of a can so as to sustain the same along its edge, of an annular cutter adapted to cut the can along but in side of said guide.

3. In a machine of the class described, the combination with a cutter adapted to cut the head of a can, of means for sustaining all portions of the can along its edge and co-operating with said cutter adapted to re-finish the edge of the can so sustained.

4. In a machine of the class described, the combination with a cutter adapted to cut the head of a can, of means for sustaining all portions of the can along its edge and co-operating with said cutter adapted to press the cut edge of the can against the sustained body thereof.

5. In a machine of the class described, the combination with a cutter adapted to cut the head of a can, of means for sustaining the can along its edge and co-operating with said cutter adapted to contour the edge of the can so sustained.

6. In a machine of the class described, the combination with a cutter adapted to cut the head of a can, of means for sustaining the can along its edge and co-operating with said cutter adapted to contour the edge of the can so sustained and press the cut edge of the can against the sustained body thereof.

7. In a machine of the class described, the combination with a cutter adapted to cut the head of a can, of a guide adapted to take over the head of the can so as to sustain the same along its edge while being cut, constructed and arranged to refinish the edge of the can so sustained.

8. In a machine of the class described, the combination with a cutter adapted to cut the head of a can, of a guide adapted to take over the head of the can so as to sustain the same along its edge while being cut, and adapted to contour the edge thereof while so sustained.

9. In a machine of the class described, the combination with a cutter adapted to cut the head of a can, of a guide adapted to take over the head of the can so as to sustain the same along its edge while being cut, constructed and arranged to press the cut edge of the can against the body thereof while so sustained.

10. In a machine of the class described, a head comprising an annular cutter adapted to cut the head of a can, and an annular guide spaced from said cutter and adapted to take over the head of the can so sustained.

11. In a machine of the class described, a head comprising an annular cutter adapted to cut the head of a can, and an annular guide spaced from said cutter and adapted to take over the head of the can so as to sus-

tain the same along its edge while being cut, constructed and arranged to refinish the edge of the can while so sustained.

12. In a machine of the class described, a head comprising an annular cutter adapted to cut the head of a can, and an annular flaring guide spaced from said cutter and adapted to take over the head of the can so sustained.

13. In a machine of the class described, a head comprising an annular cutter adapted to cut the head of a can, and an annular guide spaced from said cutter and adapted to take over the head of the can so as to sustain the same along its edge while being cut, said cutter and guide being constructed and arranged to provide an annular space beyond the cutting edge of the cutter.

14. In a machine of the class described, the combination with a frame, of a base thereon adapted to support a can, a head on said frame comprising an annular cutter adapted to cut the head of a can, and an annular guide spaced from said cutter and adapted to take over the head of the can so as to sustain the same along its edge while being cut, and mechanism for moving said base and said head relatively.

15. In a machine of the class described, the combination with a frame, of a base thereon adapted to support a can, a head on said frame comprising an annular cutter adapted to cut the head of a can, and an annular guide spaced from said cutter and adapted to take over the head of the can so as to sustain the same along its edge while being cut, constructed and arranged to finish the edge of the can while so sustained, and mechanism for moving said base and said head relatively.

16. In a machine of the class described, the combination with a cutter adapted to cut the head of a can, of means for encircling the can along its edge and outside of the line of cut, adapted to sustain the can along its edge against the action of the cutter.

17. In a machine of the class described, the combination with a cutter adapted to cut the head of a can, of means for encircling the can along its edge and outside of the line of cut, adapted to sustain the can along its edge against the action of the cutter and adapted to contour the can edge.

18. In a machine of the class described, the combination with a cutter adapted to cut the head of a can and adapted to press the cut portion outwardly against the can body, of means for encircling the can along its edge and outside of the line of cut, adapted to sustain the can along its edge against the action of the cutter.

19. In a machine of the class described, the combination with a cutter adapted to cut the head of a can and adapted to press

the cut portion outwardly against the can body, of means for encircling the can along its edge and outside of the line of cut, adapted to sustain the can along its edge 5 against the action of the cutter and adapted to contour the can edge.

20. In a machine of the class described having a cutter adapted to cut the head of a can along the can edge, characterized by the 10 fact that there is combined with the cutter an annular guide which is adapted to take over the can and sustain the can edge against the action of the cutter.

21. In a machine of the class described 15 having a cutter adapted to cut the head of a can along the can edge, characterized by the

fact that there is combined with the cutter an annular flaring guide which is adapted to take over and contour the can and sustain the can edge against the action of the 20 cutter.

22. In a machine of the class described, the combination with a tubular guide adapted to take over the head of a can so as to sustain the same along its edge, of a tubular cutter adapted to cut the can along but 25 inside of said guide.

In testimony whereof we affix our signatures this 3rd day of June, 1918.

MILTON G. CLYMER.
ARTHUR E. RITCHHEY.
